GRAPPLE

Jack Breslav, New Haven, Conn.

Application February 19, 1946, Serial No. 648,717

3 Claims. (Cl. 294—67)

1

This invention relates to grapples and more particularly to improvements in grapples especially adapted to engage and lift a pile of sheet, or plate, stock for transfer to another location.

One form of grapple adapted to the above-mentioned use is provided with a pair of opposed stock carrying bars, or angles, between which the stock in sheet or plate form, extends, either singly or in piles, with the side edges thereof resting upon said bars. These bars, or angles, are arranged to be positively moved toward and away from each other by being secured to the lower ends of one or more drop legs, or carrying arms, each of the latter depending from the outer end of a horizontally disposed and slidably mounted beam, the beams being supported to be oppositely moved in an enclosing structure by means of a hand wheel, acting through suitable gears and shafts. Such a form of grapple is shown and described in U. S. Patent No. 2,337,176, issued to Jack Breslav, December 21, 1943.

The principal object of this invention is to improve the structure of a grapple of the above nature whereby the operating mechanism and the supporting frame therefor will be of minimum height, to save overhead operating space and thus facilitate the use of such a grapple in a stock storage location having a relatively low ceiling.

Another object is to provide in a grapple of the above nature mechanism operating means of an improved structure whereby the same may be disposed within a minimum amount of space and protected against interference by associated mechanism.

A further object of this invention is to provide an improved form of grapple which will be relatively simple in construction, inexpensive to manufacture, readily manipulated, especially compact, and very efficient and durable in use.

With these and other objects in view, which will appear as the description proceeds, there has been illustrated in the accompanying drawings a form in which the features and principles of this invention may be conveniently embodied in practice, it being understood that various changes may be made within the scope of what is claimed, without departing from the spirit of the invention.

In the drawings:

Figure 1 is a top plan view of a grapple embodying the features and principles of this invention;

Figure 2 is a side view of the same; and

Figure 3 is a right hand end view of the same.

2

Referring now to the drawings wherein like reference numerals designate like parts throughout the several views, stock carrying members, to be hereinafter described, are supported by drop legs 13 and 14 secured to the outer ends of slide beams 17 and 18 respectively, and legs 15 and 16 secured to the outer ends of slide beams 19 and 21, respectively. The slide beams 17, 19 and 18, 21, are arranged to slide horizontally in opposite directions in housings 22 and 23 respectively, when gear pinions 24 and 25 respectively are rotated. The teeth of the gear pinion 24 mesh with the teeth of toothed racks 26 and 27 respectively secured to the beams 17 and 18. The teeth of the gear pinion 25 mesh with the teeth of toothed racks 28 and 29 respectively secured to the beams 19 and 21. The vertical shaft 31, to which the gear pinion 24 is secured, is journaled in a lower bearing plate 32 and extends upwardly through an upper bearing plate 33. The bearing plate 32 extends between and is secured to channel beams 34 and 35 constituting the side members of the housing 22, and the bearing plate 33 is secured to and supported on the top surface of the channel beams 34 and 35. The shaft 31 extends upwardly beyond the plate 33 and has a bevel gear 36 secured thereto above the plate 33 (see Figure 1). The vertical shaft 37 of the gear pinion 25 extends through a bearing plate 38 which extends between and is secured to channel beams 39 and 41 constituting the side members of the housing 23. The shaft 37 is secured to the pinion 25 and extends upwardly therefrom through a bearing plate 42 secured to and supported on the top surface of the channel beams 39 and 41. The shaft 37 extends upwardly beyond the plate 42 and has a bevel gear 43 secured upon its upper end. Rotation of the bevel gears 36 and 43 in unison will cause the respective pairs of slide beams 17, 19 and 18, 21 to slide in the housings 22 and 23 respectively, to move the respective drop legs 13, 15, and 14, 16 in unison toward or away from each other. The housings 22 and 23 are secured to and suspended from widely spaced apart grapple frame side beams 44 and 45 and the outer ends of the respective side members 34, 35, and 39, 41 of these housings are secured together by plates 46, 47, and 48, 49 respectively.

50 A short horizontal shaft 51, journaled in spaced apart bearing blocks 52 and 53 mounted on the bearing plate 33, has a bevel gear 54 secured thereto which is in mesh with the bevel gear 36. The shaft 51 extends beyond the bearing block 53 and has a sprocket wheel 55 secured

upon its inner end. A short horizontal shaft 56, journaled in spaced apart bearing blocks 57 and 58 mounted on the bearing plate 42, has a bevel gear 59 secured thereto which is in mesh with the bevel gear 43. The shaft 56 extends beyond the bearing block 58 and has a sprocket wheel 61 secured upon its inner end. The inner ends of shafts 51 and 56, upon which the sprocket wheels 55 and 61 are respectively secured are in opposing relation, see Figure 1. The sprocket wheels 55 and 61 are drivingly connected to sprocket wheels 62 and 63 respectively by chains 64 and 65. The sprocket wheels 62 and 63 are secured on a continuous horizontal shaft 66 extending along and disposed over the frame beam 44 being journaled adjacent each end of the beam 44 in bearing blocks 67, 68, and 69, 71 respectively. The bearing blocks 67, 68, and 69, 71 are mounted on and secured to the beam 44. A hand wheel 72, 73 is secured one upon each outer end of the shaft 66 and constitute the simplest means by which the shaft 66 may be rotated.

An elongated bar 76 is secured to and extends between the drop legs 13 and 15 to reinforce and connect them together, and a similar bar 77 is secured to and extends between and across the drop legs 14 and 16 to reinforce and to connect them together. A stock S engaging and carrying angle bar constituted by separated angle bar sections 78, 79, and 81 is supported from the drop legs 13 and 15 by being secured to the bar 76 by overlapping strips of material 82 secured to the sections and to the bar 76. The angle bar sections 78, 79 and 81 depend from the bar 76 and are disposed with one leg 83 of their angle section extending inwardly toward the center of the space between the frame beams 44 and 45. A stock S engaging and carrying angle bar, constituted by separated angle bar sections 84, 85 and 86, is supported from the drop legs 14 and 16 by being secured to the bar 77 by overlapping strips of material 87 secured to the sections and to the bar 77. The angle bar sections 84, 85 and 86 depend from the bar 77 and are disposed with one leg 88 of their angle section extending inwardly toward the center of the space between the frame beams 44 and 45.

The purpose of dividing the stock S supporting bars into separated sections, as above described, is to insure that the inwardly extending angle section legs 83 and 88 will be in alignment the entire length of the respective bars so as not to warp or unduly bend the pile of sheet, or plate, stock S being engaged and raised. Such a feature is especially desirable when the stock S supporting bars are comparatively long as such lengths of angle bars have a tendency to warp out of alignment. To further insure efficient and proper support for the pile of sheet or plate stock S, a plurality of short lengths of narrow bar stock 90 are spaced apart along the upper surface of each of the angle sections 78, 79, 81, 84, 85, and 86. Another advantage gained by providing stock supporting bars constituted by spaced apart sections is to provide spaces 89 and 91 for the uprights 92, see dotted lines in Figures 1, 2, and 3, of a stock S supporting rack and thus permit the angle section legs 83 and 88 to extend under the edges of the plate stock S a sufficient amount to properly engage and support said stock.

The grapple, as above described, is adapted to be raised and lowered by a crane, or like hoisting means, by being provided with hoist hook engageable members 93 and 94. The members

93 and 94 are herein shown as being short bars extending between pairs of spaced apart beams 95 and 96. Each pair of beams 95 and 96 extend from the frame member 44 to the other 45 and 5 are secured to the under side of the frame members 44 and 45 at the ends thereof. Being disposed in under the frame members 44 and 45 the beams 95 and 96 support the members 93 and 94 well below the high portions of the grapple 10 so that the latter may be raised from points closely adjacent the hoist frame and thus be efficiently used in locations where operating height is an important consideration, such as when the racks of stock S extend upwardly close to the ceiling 15 of the stock storage room. In some installations it is desirable to provide only one hoist hook engageable member 97 and in such instances this member 97 is supported by beams 98 and 99 which extend across the grapple frame from the frame member 44 to the member 45 substantially at the center portions thereof as indicated in Figure 1. 20

It will be understood that the novel features and principles of this invention may be embodied in other specific forms without departing from 25 the spirit and essential attributes thereof, and it is therefore desired that the present embodiments be considered as illustrative, and not restrictive, reference being had to the claims rather than to the foregoing description to indicate the 30 scope of the invention.

Having thus fully disclosed the invention, what is claimed as new and for which it is desired to secure Letters Patent, is:

1. In a grapple, a frame comprising spaced 35 apart side beams, a housing extending from adjacent each end of one frame side beam to the other side beam, a pair of slide beams in each housing, a gear rack on each slide beam, a gear pinion disposed between the slide beams of each 40 pair in mesh with the gear racks thereon, a drop leg depending from the outer end of each slide beam, an elongated bar connected to the drop legs at each side of the frame to extend along the frame, spaced stock-supporting angles connected to each of said bars, a vertical first shaft 45 for each gear pinion, a first bevel gear on the upper end of each first shaft, a second and horizontal shaft adjacent each first shaft, the inner ends of said second shaft being in opposing relation, a second bevel gear and a sprocket wheel on 50 each of the opposing ends of said second shafts, the second bevel gears being in mesh with the first bevel gears, a horizontal operating shaft mounted on one of the frame side beams and extending parallel thereto substantially the entire 55 length thereof, spaced apart sprocket wheels on said operating shaft, and a chain connecting one of the sprocket wheels on the operating shaft with the sprocket wheel on one of said second 60 shafts, and the other one of the sprocket wheels on the operating shaft with the sprocket wheel on the other of said second shafts.

2. In a grapple, a frame comprising transversely spaced apart frame beams, longitudinally 65 spaced apart housings depending from and extending between said side beams, a pair of oppositely slideable slide beams in each housing, a gear rack on each slide beam, a gear pinion between each pair of slide beams and in mesh with the gear racks thereon, a vertical shaft extending 70 upwardly from each gear pinion and to which it is secured, a bevel gear on the upper end of each vertical shaft, a short horizontal shaft mounted on each housing above said bevel gear and having 75 a bevel gear thereon in mesh with the bevel

gear below said shaft and a sprocket wheel on its inner end, the inner ends of said short horizontal shafts being in opposing relation, drop legs depending from the outer ends of each one of each pair of slide beams, an elongated bar secured to said drop legs at each side of the frame, a plurality of stock-supporting angles secured to each of said bars in spaced relation longitudinally thereof and disposed below the side beams, and a horizontal operating shaft mounted on and extending along the entire length of one of said side frame beams, sprocket wheels spaced apart along said operating shaft, and a chain connecting one of the sprocket wheels on said operating shaft with the sprocket wheel on one of the horizontal shafts and the other one of the sprocket wheels on the operating shaft with the sprocket wheel on the other of said second shafts, one of said chains extending along the inner side of each housing.

3. A grapple comprising a frame having spaced apart side beams, a housing extending from adjacent each end of one frame side beam to the other, a pair of slide beams in each housing, rotatable means between and engaging the slide beams in each housing to oppositely slide said beams in said housing, elongated bars attached to the outer ends of said slide beams, one on each side of the frame, a plurality of stock-engaging members secured to each of said bars and spaced longitudinally thereof, and means to rotate the slide beams' sliding means, including a short hori-

zontal shaft operatively connected to each of the rotatable means and mounted on each housing centrally intermediate the frame side beams, a sprocket wheel on the inner opposing ends of said short shafts, a long horizontal shaft mounted on the upper surface of one of said frame side beams and extending substantially the entire length thereof, a sprocket on said long shaft in alignment with each of the sprocket wheels on the short shafts, a chain drivingly connecting each of the sprockets on the long shaft to the sprocket wheel on the short shafts aligned therewith, and a hand wheel on one end of said long shaft, the sprockets on said long shaft being at the inner side of the adjacent housing and the hand wheel being at the outer side of the adjacent housing at one end of the grapple.
